UNITED STATES PATENT OFFICE.

JOSEPH A. CREW, OF BETTERTON, MARYLAND.

HAIR-DRYING APPARATUS.

1,255,585.

Specification of Letters Patent. Patented Feb. 5, 1918.

Application filed January 15, 1917. Serial No. 142,452.

To all whom it may concern:

Be it known that I, JOSEPH A. CREW, a citizen of the United States, residing at Betterton, in the county of Kent, State of Maryland, have invented certain new and useful Improvements in Hair-Drying Apparatus; and I do hereby declare the following to be a full, clear, and exact description of the invention, such as will enable others skilled in the art to which it appertains to make and use the same.

This invention is an improvement in driers and has particular reference to a hair drying apparatus.

An object of the invention is the provision of an apparatus, principally for use in a barber shop, for quickly drying the hair after shampoos, and to this end, use is made of a source of heat to which is connected a suction fan mounted upon a suitable frame and operated by a foot controlled mechanism also supported by said frame.

Another object is the provision of an apparatus of this character which is comparatively simple in construction, easy to manufacture and effective in carrying out the purpose for which it is designed.

The inventive idea involved is capable of receiving a variety of mechanical expressions, one of which for the purpose of illustrating the invention, is shown in the accompanying drawing, wherein:—

Figure 1 is a view in elevation of the apparatus constructed in accordance with the invention.

Fig. 2 is a top plan view.

Fig. 3 is a vertical sectional view on the line 3—3 of Fig. 2.

Fig. 4 is a section on the line 4—4 of Fig. 1.

The invention is shown in the accompanying drawing in what is now believed to be its preferred form wherein the apparatus comprises a frame generally indicated by the numeral 5 and including a top 6 having the bearings 7 mounted thereon and in which is journaled a horizontal shaft 8 having a drive wheel 10 carried thereby. This drive wheel 10 is connected to a wheel 9, carried by the frame 5, by means of a flexi-

ble element 11 said wheel 9 is rotated by a pitman connection 12 to which is attached the foot treadle 13 also journaled in the frame 5.

The suction fan 14 having an outlet 15 is mounted upon the top 6 of the frame adjacent one of the bearings 7 and has projecting thereinto the shaft 8 which operates said fan when said shaft is rotated.

Depending from the top 6 and braced by the frame 5 is a bracket 16 having a horizontal portion 17 at its bottom which supports a heating device generally indicated by the numeral 18. This device comprises a casing 19 having a plurality of air inlet 65 openings 20 adjacent its bottom and below which is mounted a burner 21 which is supplied with fuel from a suitable reservoir 22 through a connection 23 mounted in the casing 19 and projecting through the top thereof is a frusto-conical heating drum 24 having a centrally disposed rod extending vertically therethrough upon which is mounted a plurality of baffle plates 26 for diffusing the heat from the burners 21. Pivottally 75 mounted upon the upper end of the rod 25 and resting upon the top of the drum 24 is a ventilator plate 27 having a number of openings 28 therein. The casing 19 is provided with an outlet 29 which is connected 80 to the suction fan 14 so that when the latter is operated the heat from said casing is drawn into the same from the casing 19 and ejected through the outlet opening 15 of said fan whereby the hair may be quickly 85 dried.

From the foregoing description it will be apparent that when the treadle 13 is operated the shaft 8 will be rotated and the fan 14 driven so as to draw the heated air from 90 the casing 18 into said fan and then out through the outlet opening 15 thereof.

What is claimed is:—

An apparatus of the character described comprising a frame having a top, bearings 95 carried by said top, a rotary shaft journaled in said bearings, a suction fan mounted on said top and driven by said shaft, a bracket depending from said top and having a horizontal portion, a heating device sup- 100

ported by said horizontal portion and including a casing, a burner below said casing, means for supplying fuel to said burner, a heating drum within said casing, and 5 a connection between said casing and said fan for supplying heated air to the latter.

In testimony whereof, I affix my signature, in the presence of two witnesses.

JOSEPH A. CREW.
